C. A. VADEN

MECHANICAL MASSAGE APPARATUS

Filed July 12, 1926

UNITED STATES PATENT OFFICE.

CLAUDE A. VADEN, OF WHEELING, WEST VIRGINIA.

MECHANICAL MASSAGE APPARATUS.

Application filed July 12, 1926. Serial No. 121,816.

This invention relates broadly to kinesitherapeutic apparatus, and more specifically to a vibratory muscle massaging and exercising device.

5 The primary object of the invention is to provide a simple and improved form of mechanical apparatus of oscillatory belt type whereby massage of the muscles of the body and/or limbs may be conveniently effected.

10 A further object is to provide a device of the character mentioned embodying means whereby the belt attachment may be readily adjusted to various levels or elevations, as 15 desired.

In describing the invention in detail, reference is herein had to the accompanying drawings, in which—

20 Figure 1 is a top plan view of the invention;

Figure 2 is a side elevation of the same;

Figure 3 is an enlarged detail section on line 3—3, Fig. 2; and—

Figure 4 is a section on line 4—4, Fig. 1.

25 Referring to said drawings, 1 indicates a suitable base which has stationarily mounted thereon adjacent to an end thereof an upright standard 2. Fixed on said standard adjacent to its upper and lower ends, respectively, are brackets 3 and 4 which form bearings for a vertical shaft 5. Said shaft has rigidly mounted thereon adjacent to its lower end a crank-arm 6 to which is pivotally connected an end of a connecting 30 rod 7 which connects at its opposite end with an eccentric 8 carried by a drive shaft 9 journaled in bearings 10 upon the base 1. The coupling intermediate the crank arm 6 and rod 7 consists of a loop member 6^a to 35 which the crank arm is pivotably connected by means of adjustable pivot pins 6^b and 6^c. The loop member 6^a has a rearwardly extending part 6^d to which the forward end of the rod 7 is connected. The shaft 9 is 40 suitably driven, as by an electric motor 11 which, as herein shown, is driven by a belt 12 connecting pulleys 13 and 14 fixed on the rotor and drive shafts, respectively.

45 Mounted for vertical adjustment on the shaft 5 is a rocker member 15 through which oscillatory movements imparted to said shaft through the connecting rod 7 are communicated to a massaging belt 16, indicated in dotted lines in Figs. 1 and 2, which has 50 its ends attached to said member 15. One or more pairs of horns, as 17 and 18, located

on the opposite end portions of the rocker member 15 may be provided for receiving thereon loop-like ends 16^a of the detachable belt 16.

60 An adjusting screw 19 carried by the rocker member 15 is designed to be threaded into binding seated relation to the shaft 5 for securing said member in adjusted position on and in rigid relation to said shaft. 65

In practice, the massaging belt 16 having been adjusted or applied to embrace the portion of the body or limbs of the user which is to be acted upon, the motor 11 is started for imparting forward and reverse longitudinal movements to said belt, through the intermediate mechanism hereinbefore described, said mechanism comprising, in turn, the drive belt 12, the shaft 9, the connecting rod 7, the oscillatory shaft 5, and the 70 rocker member 15.

75 For partially relieving the mechanical parts of the structure from shocks and resultant vibration which would otherwise be incident to the driving of the mechanism in the manner described, the connecting rod 7, herein shown as of flat bar form, has a portion 7^a thereof suitably reduced in thickness to render it readily flexible, or resilient, under the longitudinal strains imposed 80 thereon in the reciprocating movements thereof.

85 The extent of the rotary oscillating movements imparted to the shaft may, obviously, be regulated by adjustment of the position 90 of the connection made between the connecting rod 7 and the crank arm 6.

95 What is claimed is—

1. In a massage apparatus, a base, a vertically disposed standard on said base, a pair of forwardly extending horizontal brackets secured one to each end of the standard and having vertical openings therethrough, a vertically disposed rotary shaft having its ends journaled in said openings, said shaft being disposed in spaced parallel relation to the standard, a vertically adjustable transverse belt holding member on said shaft between the brackets, a pair of spaced belt engaging fingers carried by the belt holding member, a crank arm secured to and extending outwardly from said shaft, a loop member through which the free end of said crank arm extends having a rearwardly extending part, 100 driving means for the shaft, means to adjustably secure the loop member to said 105

crank arm, and a pitman rod having one end secured to the driving means and its opposite end connected to the rearwardly extending part of the loop member whereby oscillatory movement is imparted to the shaft and massage means.

2. In an apparatus of the character described, a base, a vertically disposed standard fixed on said base, forwardly extending brackets carried by said standard adjacent to its upper and lower ends, a shaft having its ends journaled in said brackets and disposed in parallel relation to said standard, a member transversely mounted and vertically

adjustable on said shaft, said member having belt-engaging fingers thereon, a crank arm attached to and extending laterally from said shaft, rotary driving means, a pitman having an end attached to said driving means, and means connecting the opposite end of said pitman to said crank arm, said connecting means being adjustable relative to said shaft to regulate the extent of oscillatory movement imparted to the latter through said crank arm.

In testimony whereof, I affix my signature.

CLAUDE A. VADEN.
